AMUSEMENT DEVICE

Herbert N. Ridgway, Winthrop, Mass.

Application April 14, 1939, Serial No. 267,808

2 Claims. (Cl. 104—73)

My present invention is a novel and improved amusement apparatus, and more particularly relates to a boat, or a plurality of boats, each adapted to carry passengers, and each arranged to be propelled or drawn in a tank or runway of water, with provision for effecting a jumping or leaping action of each boat and simulating a high-speed motor craft.

Important features consist in the construction and arrangement of means which will propel each boat from a single source of power and yet permit each boat full freedom of movement, as well as displacement for the load of passengers carried and, furthermore, to allow the pitching action incident to the wave effect upon each boat independently of the other, and all while being moved at any speed desired from the common source of power.

A further important feature consists in the provision of safety means which will eliminate the danger of rocking of a boat while still permitting the pitching action and, particularly, the capacity for jumping or leaping from the water when desired without interruption or interference with the driving mechanism.

A still further and important feature consists in the provision of means automatically actuated so that when each boat is at rest or at the end of the ride, it will be independently and automatically swung into contact with the edge of the tank to facilitate loading and unloading of passengers, and also will be automatically drawn away from the tank edge and loading position as soon as the moving mechanism starts and each and all boats are "under way" in the tank.

A still further important feature of my present invention consists in the safety controlling features, whereby, when each boat is actuated to jump, leap, or fly thru the air simulating high-speed motor boats hitting a wave, it is controlled in its path of movement and line of travel while still permitting freedom of action of the boat and insuring safety in flight and landing without affecting the operation of any preceding or succeeding boat in the apparatus and without interruption in the propelling power.

In carrying out my present invention I contemplate providing a substantial tank or runway filled with water, preferably of oval shape or round, and of sufficient capacity to give straight-away stretches for attaining speed and effecting the jumping or flight actuations.

In order to propel such a fleet of boats, I prefer to utilize an endless cable submerged within

the water, and preferably concealed from view, and operate the same around suitable pulleys, drums, and guideways to control the direction and line of travel of the boats, providing a suitable source of driving power to one or more of such drums or pulleys, together with suitable tensioning and adjusting means which will tighten the endless cable, as desired, and also facilitating the varying strains and stresses in the operation of the mechanism of the apparatus.

In order to effect the jumping or flight actuation, I prefer to arrange a plurality of suitably inclined planes or platforms which can be operated at will, thus to permit the free floating of each boat over the same, when desired, and when attaining speed, and then to throw the jumping or leaping platform into position so that a boat, or successive boats, may ride up over the platform and leap or jump thru the air to a landing in the water beyond the platform, while being continuously connected to the endless cable and driving means.

Important features consist in providing operating and controlling means for the "jumping" platforms so that same may be brought into operative position or depressed below the draft of the boats passing over same at will; means for insuring the individual action of each boat both during travel at speed and when the propelling means is discontinued, so that each boat will individually and automatically swing into loading and unloading contact at the edge of the tank; and other details and advantages will be hereinafter more fully pointed out and claimed.

Referring to the drawings illustrating preferred embodiments:

Fig. 1 is a plan view of an oval tank and installation utilizing two drums from which a propelling cable is led;

Fig. 2 is a cross-sectional view on an enlarged scale on the line 2—2 of Fig. 1;

Fig. 3 is an enlarged cross-sectional view on the line 3—3 of Fig. 1;

Fig. 4 is a fragmentary cross-sectional view on the line 4—4 of Fig. 1;

Fig. 5 is a fragmentary cross-sectional view showing a "leaping" platform in operating position;

Fig. 6 is a view corresponding to Fig. 5 illustrating the anti-friction platform construction;

Fig. 7 is a detailed view of the platform-operating and locking means, and

Fig. 8 is a diagrammatic plan view of a rotary embodiment of the invention.

Fig. 9 is a fragmentary view, partly in cross-section, illustrating an attaching means for the modification of Fig. 8.

Referring to the drawings and the form illustrated in Figs. 1 to 7, an oval-shaped tank is shown, having a bottom 1, sides 2, and a marginal platform 3 overhanging the inner surfaces 10 of the sides 2 slightly, as indicated in Fig. 2, wherein any desired level of water, indicated at 5, is supplied. Positioned in the bottom portion of the tank near opposite ends are two grooved drums or wheels, one as indicated at 6 being 15 mounted on a fixed shaft 7, and the other 8 being mounted on a pivot 9 carried in a movable slide 10.

These drums 6 and 8 may be made in any form desired, being herein illustrated as comprising disc-like top and lower sides united by a rim 11, leaving an outer groove 12 in which an endless cable or rope 15 is led and extending around each of the drums. The drum 8 is arranged for sliding adjustment for assembling, 25 and has a pulley tensioning member, this being best shown in Figs. 1 and 2.

For this purpose I provide guideways 18, 19 at each side of the sliding bearing 10 carrying the pivot 9, these guideways being grooved and 30 being adapted for adjustment under yielding tension by tightening the threaded screws 18, 18 which pass thru tapped recesses in the cross-bar 19 secured to the bottom portion 1 of the tank, each of said screws 18 having their inner 35 ends encircled by coiled springs 28, 29, bearing between collars 21, 21 adjustably secured on each of the screws 18 and with the opposite end against the slide 10. A further guide 22 may be supplied, if desired, and a recess 23 in the slide 40 10 permitting the free ends 24 of each of the screws to project for adjustment and manipulation is also provided.

It will thus be seen that the cable 15 when fitted, and with the adjusting screws 18 tightened will always exert a yielding tension thru the springs 28 on the adjustable drum 18, thus providing for varying loads on the cable 15 and yielding action as the boats travel around the rim of the groove 12 of each drum during the 50 operation of the apparatus.

Any suitable driving means may be arranged but, as herein shown, I may provide a direct drive on the shaft 7 from a motor 25 underneath the bottom 1, which motor operates thru a reduction 55 gear 26 and bevelled gears 27 and 28, the latter keyed to the shaft 7, which shaft passes thru a suitable bearing 30 having a recess to receive a packing material 32 and a follower 33 thru which the shaft 7 also passes. A supporting collar 31, 60 as shown in Fig. 3, is also provided.

In order to facilitate the rotative operation of the drums 6 and 8, I provide a plurality of idler rolls 35, 35 at any suitable or convenient position, substantially as illustrated in dotted lines in Fig. 65 5, and approximately as shown in Fig. 3, over which the outer rim portions of the drums may rest and travel. Secured to the endless cable 15 are a plurality of freely-floating and load-carrying boats, each adapted to carry its own load 70 while floating in the tank, and a description of one will, therefore, be sufficient for all said boats.

Such boats may be of any desired capacity, and comprise a suitable hull 40 having, as herein shown, longitudinal seats 41, 41, an after deck 42, 75 a forward deck 43, and sprayhoods 44. Posi-

tioned at the forward end of each boat is an open tube or hollow shaft 45 extending from the bottom to and thru the forward deck 43, which constitutes a bearing for the staff 46.

This hollow shaft 45 is set in an angular position (as best shown in Figs. 5 and 6) relatively with the longitudinal axis of the boat 40, as best shown in Figs. 5 and 6, which is a most important feature, and actuates the boat 40 to swing laterally from its line of travel when the cable 15 is at rest or moving very slowly. As each boat naturally tends to swing outwardly, owing to the relative angle of the staff and the inherent buoyancy of the boat, this inclination of the staff 46 and shaft 45 acts to swing the stern portion 43 of the 15 boat in to the rim 3 of the tank, so that the aft deck 42 of the boat will be in convenient position for passengers to step into or out of each boat while same is thus at rest.

Preferably, I so position the spacing of the surrounding rim and the line of travel of the boats that the length of the boat from the staff 46 to the stern will be slightly greater from that of the cable to the rim and, hence, the stern of each boat will contact at a slight angle with the rim 3 and not be swung by the same, as indicated in dotted lines at 50 in Figs. 1 and 8.

The staff 46 extending freely thru the hollow shaft 45 thus permits each boat to rise and fall with its varying load to seek its own displacement as well as to lift and drop and pitch slightly, due to any wave effect, but the rigidity and strength of the staff 46, together with the guiding instrumentalities, will restrain the rocking action of the boat and, hence, provide an important safety factor.

Each staff extends downwardly and carries an anti-friction roller 51 adapted to travel on the bottom 52 of a guiding track, this track having upstanding portion 54 with lugs 55 and 56 adapted to bear against the staff 46 (see Fig. 4) together with the upper slot 57 thru which the staff passes. Between the slot 57 and the bearing strips 55 and 56, I provide a clamp 60 arranged to be secured around the staff 46 and to clamp the endless cable 15, this clamp comprising a pair of members and joined by clamping screws 62, 62.

Preferably I arrange this clamp so as to impart a slight angular position to the staff 46 particularly when the same swings off the guiding strips 50 on the parallel portion of the line of travel of the endless belt 15 and on to the drums 6 and 8 so as to give the effect of "banking" the boat around a curve and offset the centrifugal force thereto and also to more accurately simulate a speed boat 55 when making a turn.

With the construction as thus far described, the drums 6 and 8 are positioned in the track, the endless cable 15 is fitted, the side guiding tracks 53 and 54 are applied and, preferably, mounted 60 on sleepers 65 to have them properly spaced and carry the track in alignment with the grooves 12 in each of the drums, and thereupon the staffs 46 are clamped to the cables at predetermined spaced intervals and each boat 40 mounted thereon.

The staff 46 is the only driving connection between the boat and the endless cable and, thus, permits free pivotal action of the boat as it swings around the drums while the tension springs 20, 20 will hold the belt in yielding tension and permit such variation in the load and strain on the endless cable 15 as may be incident to the operation of the apparatus, as well also as the slight extra action of the staff around the rim of the drums, the drum 8 yielding for all purposes.

In order to allow for any centrifugal action of the boats as they swing around the drums and to enable the staff to engage the guides 54 and 55, I provide a flanged portion 66 on the outer rim of 5 each of the straight portions of the guides in the line of travel of the belt, as shown in Fig. 1.

As thus far described, the boats may be readily operated and with the cable at rest, each boat will swing in to the edge of the tank with the 10 stern portion of each in contact with the rim 3. Upon starting the motor 25, the drum 6 will rotate and impart motion to the cable 15 and, hence, to each of the boats, which will readily and rapidly turn in the line of travel with the cable, 15 swinging the stern portion of each boat away from the tank and practically in alignment with the pulley of the cable thru the staff 46 and tubular bearing 45 of each boat.

I may, if desired, form a continuous outer 20 guard, as shown at 36, Fig. 1, around the outside of either drum as a further safety factor in case of breakage of the endless cable 15.

In order to provide the "jumping" or "leaping" effect desired to simulate the action of a speed 25 boat in rough or wavy conditions, I have provided a plurality of, what I have termed as, "leaping" platforms. These platforms are ordinarily at rest sufficiently submerged under the level of the water 5 in the tank so that each boat, even 30 when loaded to its capacity, will float freely thereover but each platform may be brought into operative position at will. If desired, operating means can be attached to each platform, but I have herein shown a single operating device for 35 a plurality of platforms which may thus be brought into operative action simultaneously and after the series of boats have attained a proper speed of travel so as to produce a leaping, jumping, or flying effect, with the consequent thrilling sensation to the riders.

Any suitable or desirable means can be utilized 40 for effecting the leaping action, but as herein shown, I have provided a pair of flexible members 70 and 71 adapted to be spaced at each side 45 of the staff 46 and, hence, of the slot 57 in the guideways, which members may be of metal, preferably curved, and adapted to present an inclined plane in the line of travel of the boat 40 of which said boat will be thrown during its forward motion and, hence, will effect a flying leap 50 thru the air and back into the level of the water.

A simple and efficient operating means consists 55 in hinging the rear portion of each of these curved members 70 to supports 72, 72 by pivots 73 and with the link 75, hinged as shown at 76, to a forward portion of the members 70 and 71 and with the bottom of the link 75 hinged to a sliding plate 77 adapted to slide in side guides 78, 78, as best illustrated in Figs. 1 and 5. Movement of the slides 77 toward the rear post 72 or 60 against the line of travel of the boats will act to raise the members 70 and 71, lifting them into the line of travel of the boat and, hence, creating an inclined or sliding plane up which the boat 65 can readily travel, while still driven forward by the cable 15 because of the sliding action of the staff 46 in the hollow shaft 45, as will be appreciated.

I have here shown two such leaping platforms, 70 and I have arranged to operate both simultaneously by providing a cross-bar 80 pivoted at 81 to the bottom 1, and with the opposite ends of the cross-bar 80 being slotted and engaging pivots 82 attached to each platform. A link 84 pivoted at 85 at one side of the cross-bar pivot 81

extends thru a guide 86 and to one end of the operating lever 88, the lower end of the lever and the inner end of the link 84 being pivotally connected at 89, as best shown in Fig. 5. The lever 88 is fulcrumed on a pivot 90 secured to the rim 5 of the platform, and I arrange a ratchet 91 and spring 92 to swing the lever 88 into engagement with said ratchet and hold the same into the position to which it may have been moved by the operator. 10

Thus the platforms 70 and 71 will be locked in operative or inoperative position, as desired, until the lever 88 is manipulated to change or release the same. A rib or tooth 93 is fitted on the lever 88 for engagement with the enlarged member 91, as illustrated in Fig. 7. 15

In Fig. 6 I have illustrated an anti-friction type of platform, comprising a pair of side members 94 carrying a series of rolls 95, 95 on pins or axles 96 extending between the side member 94, 20 which is similarly supported, pivoted, and operated as described in connection with the members 70 and 71. 25

In Fig. 8 I have illustrated a modified form wherein a large drum or disc 100 is employed in 25 a circular tank 101, having a rim 102 in which the series of boats 40 are swung into rotative action. The disc 100 is mounted on a shaft 103 and actuated by a motor and reduction gear thru bevelled gears similar to that illustrated in Fig. 3, 30 and shown in dotted lines in Fig. 8.

In this form I provide the top edge 106 of the disc 100 and the bottom edge 107, thus providing a predetermined angle to which the staff 46 can be secured by a bolt, or in any other desired 35 manner, as shown in Fig. 9.

Also, it will be appreciated that, instead of utilizing a disc or drum, either in the form shown in Fig. 1 or 8, I may construct a rim or ring-like structure which will carry the cable or boat-attaching means and be driven in any suitable 40 manner. In the particular form shown in Fig. 8, owing to the constant centrifugal action of the boats, a "leaping" platform 105 with operating means can be positioned immediately outside the 45 line of travel of the attaching staff 46, and a suitable jumping, leaping, or flying operation will be imparted to each boat 40 in this form, as will be appreciated.

Thus, it will be seen that I have developed an 50 extremely simple but highly efficient apparatus to produce interesting, amusing, and thrilling riding effects, together with most important safety factors, and also automatic means and mechanism which will cause each boat independently to swing into loading and unloading contact with the sides or landing portion of the tank in which the boats are floating as soon as the driving power stops. This is a very important factor, because, in case of unexpected 55 stoppage of the driving power from any means, each boat will swing at once into position to unload its passengers. Also, the double bearing for the driving staff prevents rocking of the boat, thus preventing the danger of carelessness by the passengers in loading or unloading, or the efforts of inconsiderate persons trying to rock the boat. 60

The yielding tensioning means is also most important as it prevents undue strain on the driving cable, drums, and staff; while the arrangement for inclining the staff, particularly in banking around curves and to aid in the automatic tendency to swing the stern of the boat into the landing position, is most important; while the 75

freedom and capacity of each boat to sustain its load to follow wave actions and to simulate a speed boat jumping over a wave thru the air and landing accentuates the thrilling effect of riding in this amusement apparatus.

5 While I have described the boats 40 as simulating a conventional boat, it will be appreciated that any floating vessel of any shape or size, such as skiffs, punts, or even tubs, or the like may be 10 utilized.

I claim:

1. Amusement apparatus comprising a tank of water and a plurality of passenger carrying boats adapted to float thereon each boat having substantial length, breadth, and depth, with capacity for carrying a plurality of passengers therein; driving means for said plurality of boats pivotally connected to each boat at a point forward of its lengthwise center and adapted to draw said boats 20 around a predetermined path in said tank, movable mechanism arranged in the line of travel of said boats and normally permitting each boat to float freely over said mechanism, and means operable at will to force said mechanism in contact 25 with any one of said boats to cause them to rise from their normal displacement in the water during the continual travel thereover to produce a

jumping effect on each boat independently of each other, said pivotal driving connection to each boat controlling the sidewise rocking of each boat independently of each other boat and irrespective of its load of passengers.

2. In amusement apparatus of the kind described, a plurality of passenger carrying boats floatable in a tank of water each boat having a substantial length, breadth, and depth, with capacity to support a plurality of passengers on its own displacement in said tank, means to move each boat through water in said tank by connecting means to each boat at a point forward of its lengthwise center, and permitting each boat to seek its own displacement and to follow wave inclinations, said movable connecting means being attached to a towing cable and being held in predetermined vertically inclined position by a track beneath the water level, said track and towing cable being positioned relatively with respect to 20 a side of the tank to cause said boat to follow a pre-determined path upon stoppage of the towing mechanism where-by the rear of each boat will swing on said connecting means to come to contact with the edge of the tank.
